UNITED STATES PATENT OFFICE.

PETER M. KLING, OF ALLEGHENY, PENNSYLVANIA.

SEMICONVERTIBLE CAR.

No. 880,541.

Specification of Letters Patent.

Patented March 3, 1908.

Application filed October 2, 1905. Serial No. 280,912.

To all whom it may concern:

Be it known that I, PETER M. KLING, a citizen of the United States of America, residing in the city of Allegheny, in the county 5 of Allegheny and State of Pennsylvania, have invented certain new and useful Improvements in Semiconvertible Cars, for which the following is a specification.

My present invention relates to semiconvertible car construction and has for its object to so construct the window posts of a car that too much lateral space between the panels and lining or too much top space in the car will not be taken up by the upper 15 sash section.

Heretofore it has been proposed to have two superposed sashes for a car window. It has also been proposed to have both of said sashes dropped into suitable pockets between 20 the panels and lining. Where it is desired to equip the car with cross seats, this has involved too much lateral space. It has also been proposed to have both sashes moved upwardly into the top of the car. This involved too much head space where the 25 height of the car was necessarily limited. It has also been proposed to have the upper sash moved upwardly to retracted position and the lower sash moved downwardly to re- 30 tracted position. The method in which this has been done heretofore has involved either a special construction of car frame, impairing the interior appearance of the car, or it has involved too much top space interfering 35 with tall people.

My present invention relates to that class of semiconvertible car construction for which Letters Patent Number 693,611, were issued February 18, 1902 in which one sash, 40 the upper one, is moved upwardly to retracted position and the other, the lower one, is moved downwardly to retracted position. In a semiconvertible car construction made in accordance with the present invention an 45 extremely small proportionate amount of head space and lateral space is utilized and the interior appearance of the car is improved. My construction is adapted to any well known construction of car frame and 50 does not necessitate a special construction of the car frame provided therewith.

My invention is clearly described in the following specification and illustrated in the accompanying drawings, in which like reference characters refer to like parts and in 55 which

Figure 1 is a vertical section of one side of a semiconvertible car body showing the windows closed. Fig. 2 is a similar view on a larger scale. Fig. 3 is a vertical section of 60 the other side of a semiconvertible car body showing the windows open.

1 is the roof of the car, 2 the head lining, contiguous to the roof, 3 the filler, 4 the upper board or plate of a vertical side car-body, 5 65 the curtain roller pocket, 6 the curtain runner, 7 the lower sash which is rectangular and straight, 8 the upper sash section which is curved in form carrying the pane 9 which is preferably straight but which may be curved 70 to conform to the shape of the upper sash section.

10 is a single sash pocket for the upper sash section 8 which is constructed in curved parallel lines and substantially tangential to 75 the side and the roof of the car and extends upward only a short distance into the space between the head lining 2 and roof 1. 11 is a car post in which the pocket 10 is located.

By forming the upper sash section 8 in 80 form of a curve less room is used in forming the pocket into which the sash section 8 is pushed when the window is opened, since the sash section may be shifted from the vertical plane it occupies when projected or lowered 85 to the diagonal plane it occupies when retracted or raised without materially decreasing the head space in the upper corner of the side of the car.

It will be noted that a curved pocket 90 conforms more nearly to the corner of the side of a car of substantially rectangular construction than would a straight pocket which in order to receive its sash section must be disposed diagonally across the corner of the side 95 of the car. By constructing the upper sash section and its pocket in the form of a curve greater ease of operation is produced over that form of straight sash section and pocket where the sash section is abruptly changed 100 from one plane to another in its retraction, such for instance as where the upper sash section is swung on a pivot traveling in the guideways and thrown across the corner of the side of the car. Since I have provided a 105 satisfactorily working upper sash section I am enabled to employ a straight lower sash 7 which is dropped into the usual pocket 12 between the panel and lining of the car. As the lower sash panel is straight and the upper 110 sash pocket terminates at its lower end adjacent to the upper end of the lower sash panel

and is held toward it in a curve, the curved upper sash section when down as shown in Figs. 1 and 2 is forced by the curve of the sides of its guiding pocket against the upper rail of the lower sash, thus holding it from vibration.

This improvement is especially advantageous in the construction of cars designed for use in subways and tunnels, wherein the height of the car is necessarily limited and wherein overhead ventilation is necessary and it is desirous to make the lower sash immovable.

While I have stated in the specification that the lower sash 7 is dropped into a suitable pocket I do not wish to be limited to such an arrangement since it may be desirable to make lower sash 7 rigid to prevent passengers from thrusting their heads or limbs out of the windows.

Having thus described my invention the following is what I claim as new therein and desire to secure by Letters Patent:

1. A semiconvertible car comprising a vertical side body, a roof, a head lining contiguous to the roof, an upper board and a post formed with a single slightly curved pocket

for the upper sash section constructed with parallel sides, and extending a short distance beyond the lower edges of the roof and the head lining, and approximately tangential to said vertical side body, and with a lower pocket, a short curved sash section shiftable in said curved pocket and a lower sash, in said lower pocket, against the upper rail of which the curved sash section is forced to hold the lower sash from vibration.

2. A semiconvertible car comprising a vertical side body, a roof, a head lining contiguous to the roof, an upper board and a post formed with a single slightly curved pocket for the upper sash section constructed with parallel sides, and extending a short distance beyond the lower edges of the roof and the head lining, and approximately tangential to said vertical side body, and a short curved sash section having a flat pane set therein as a chord to the curve of the curved sash section, and shiftable in said curved pocket.

PETER M. KLING.
